BOTTLE CARRIER

Carlo J. Ballato and Patrick F. Kearins,
Philadelphia, Pa.

Application July 18, 1950, Serial No. 174,462

1 Claim. (Cl. 214—309)

1

This invention relates to apparatus for carrying and handling a plurality of bottles simultaneously, and is more particularly directed to a device for removing a group of bottles from a compartmentalized case or carton.

It is customary practice for empty beverage bottles to be returned to the bottler so that they may be cleaned and refilled for subsequent distribution. This of course, requires the bottles to be removed from the standard cases and then moved to a convenient location for the ordinary sequence of washing and refilling operations. Heretofore this removing operation has been performed manually and considerable time has therefore been lost due to the fact that one individual cannot carry in his hands more than four bottles at a time. As is well known, the standard cases hold twelve to twenty-four bottles, thus at least three or six trips are required by one individual in order to empty one case. Even though the case may be positioned directly alongside a conveyer belt, it will still be apparent that considerable time is required to empty a case of bottles manually. Furthermore, there is always some breakage incident to manual removal of the bottles.

The present invention is directed to a light-weight, simple, inexpensive device by which the operator can in one motion remove all the bottles from a beverage carton and deposit them simultaneously on a conveyer belt or at any other desired location. The device is characterized by a plurality of inverted funnel-shaped guides for the tops of the bottles, together with toggle-actuated claws for each funnel which grip the bottle necks when properly positioned in the guides. The framework of the device includes controls and operating structure for the claws as well as means for stripping the carton or case from the bottles in the event that it does not fall away from the group of bottles as soon as they are lifted.

A primary object of the invention therefore, is to provide a simple, lightweight device for simultaneously grasping a plurality of bottles by the neck, whereby the bottles may be transported in a suspended condition.

A further object of the invention is to provide improved control means for actuating the claws of a bottle handling device.

A further object of the invention is to provide stripping means for a bottle handling device, whereby the bottle case may be quickly removed from the bottles when they are suspended in an elevated position.

2

A further object is to provide a bottle carrier having improved electrical means for suspending a group of bottles therefrom.

5 A further object is to provide a bottle carrier having improved pneumatic means for suspending a group of bottles therefrom.

A still further object of the invention is to provide an improved fluid selector valve for a pneumatically operated bottle carrier.

10 Further objects will be apparent from the specification and drawings in which:

Fig. 1 is a perspective of an improved bottle handling device constructed in accordance with the invention;

15 Fig. 2 is a side view of the structure of Fig. 1, shown just before removing a group of bottles from a bottle case;

Fig. 3 is a view similar to Fig. 2, illustrating the action of the strippers;

20 Fig. 4 is an enlarged vertical section as seen at 4—4 of Fig. 1;

Fig. 5 is an enlarged fragmentary vertical section as seen at 5—5 of Fig. 1;

25 Fig. 6 is an enlarged fragmentary section as seen at 6—6 of Fig. 4, showing the upper portion of the structure with the cover removed;

Fig. 7 is an enlarged fragmentary detail of one of the guide and claw assemblies partly broken away;

Fig. 8 is a top view of the structure of Fig. 7;

Fig. 9 is a fragmentary detail showing the operation of one of the claw assemblies and the hand lever for retaining the jaws in an open position;

30 Fig. 10 is a perspective of a modified form of a bottle handling device;

Fig. 11 is an enlarged sectional detail as seen at 11—11 of Fig. 10;

35 Fig. 12 is a diagrammatic showing of the connections for the fluid actuating cylinders and control valve;

Fig. 13 is a side view of an improved six-way fluid control valve especially adapted for use with the structure of Fig. 10;

40 Fig. 14 is a vertical section as seen at 14—14 of Fig. 13;

Figs. 15—17 show the interior of the valve structure of Figs. 13 and 14 in various operating positions;

45 Fig. 18 is a perspective of the valve rotor;

Fig. 19 is a section as seen at 19—19 of Fig. 18; and

50 Fig. 20 is a fragmentary sectional detail as seen at 20—20 of Fig. 16.

55 The present device comprises essentially the

provision of twelve cone-shaped inverted guides which are diametrically slotted to permit lateral movement of a pair of claws therethrough. The claws and guides are supported on a framework which is vertically movable with respect to the handle structure of the device so that such vertical movement actuates the claws in accordance therewith. In one form of the device, we employ a pneumatic cylinder for effecting the aforesaid relative movement. Another form uses a solenoid for the same purpose.

In addition to the above relative movement for actuating the claws, the framework also carries four vertically reciprocating plungers which upon proper operation of a switch or valve, are caused to move downward to strip the case from the bottles after they have been supported by the claws and framework.

Referring now more particularly to Figs. 1-9, a bottle handling apparatus in accordance with the present invention having electrically actuated claws and strippers, comprises a pair of side rails which serve as hand grips 25 and 26. The weight of the apparatus, as well as the weight of the bottles, is supported on grips 25 and 26 through stationary frame members 27 and 28 which are secured to the grips by means of nuts 29, 29. Frame members 27 and 28 extend upwardly and centrally to form a substantially rectangular section 30 to which there is welded a U-shaped supporting bracket 31 (Figs. 4 and 5). The actuating solenoid 32 for the claw assemblies 33, 33 is secured to the bottom of bracket 31 by means of rivets 34, 34. Likewise, the bracket 31 is rigidly secured to an inverted transverse channel 35 by means of rivets 36 (Fig. 6). Braces 37, 37 likewise connect section 30 to channel 35 and are secured thereto by means of nuts 38, 38. Channel 35 forms the central supporting member for three longitudinal stationary shafts 40, 41 and 42 which are anchored therein and which provide the upper support for the claw assemblies 33, 33. Shafts 40, 41 and 42 journal the upper links 43, 43 of the tongs 44 for each claw assembly 33. Suitable collars or spacers 45, 45 of various lengths are used on the shafts between the upper links 43, 43. The center shaft 41 is extended at either end and is anchored in the grips 25 and 26 (as shown in Fig. 5). This completes the description of all the relatively stationary structure which is immovably secured to the grips.

The reciprocating framework comprises lower transverse channel frame members 50, 50 to which there are attached three longitudinal channels 51, 51, 51 as shown in Figs. 4 and 5. Channels 51, 51 are substantially in alignment with the rows of bottles 52, 52 when in a compartmentalized case 53. A lower housing or cover 54 is secured to transverse angle members 55, 55, as shown in Fig. 5. Shafts 56, 57 and 58 are mounted in housing 54 and these shafts also provide the lower pivoting connection for lower links 59, 59 of tongs 44. Spacing collars 60, 60 may also be used between the links 59 in a manner similar to the spacers 45 on shafts 40-42. Vertical frame members 61, 61 and 62, 62 form upright extensions for channels 51, 51 and the vertical members 61 are slotted at their upper ends to receive shafts 40 and 42 and to permit vertical reciprocation with respect to the shafts. It will be noted from Fig. 4 that the center upright frame member 62 terminates below the center shaft 41, whereas the end frame members 61 and 62 are extended. The construction at the op-

posite end of the device is identical to that shown in Fig. 4.

The movable armature 63 of solenoid 32 is pivotally attached to a platform 64 by means of a pin 65 (Fig. 4). Platform 64 is mounted on and moves with transverse angle frame members 66 and 67 through four braces 68, 68. Frame members 66 and 67 are secured to the other framework through the lower housing 54 to which they are riveted at 69, 69, and the intermediate housing 70 is likewise secured to the lower framework at this point. Upper housing 71 forms a continuation of intermediate housing 70 and is readily removable by means of machine screws 72, 72. It will thus be understood that the housings and the framework are all movable as a unit with platform 64 and that the grips 25, 26 together with their associated framework, are held stationary insofar as the rest of the apparatus is concerned.

Referring now to Figs. 7-9, the lower part of each claw assembly 33 comprises an inverted conical shaped funnel 75 which is secured along the under surface of frame members 51, 51 (shown in Fig. 4). The lower edge of the funnel 75 is reverse rolled at 76 and the funnel is slotted at diametrically opposite portions 77, 77 as shown in Figs. 7-9. Links 59, 59 of the tongs assembly extend downwardly and are provided with jaws 78, 78 which have semicircular arcuate recesses oppositely disposed to each other. When the claw assembly is in the gripping position (as shown in full lines in Fig. 7), jaws 78, 78 are tightly engaged underneath the flared neck 79 of the bottles 52. It will be understood that the shape and movement of the claw assemblies is such that in the event the operator fails to engage the jaws 78, 78 under the flare 79, they will nevertheless catch under the uppermost annular rim 80 of the bottles, and in this event operate just as effectively.

Vertical relative movement between the movable framework and the stationary structure or framework that is integral with the grips, raises shafts 56, 57 and 58 which in turn close the claws simultaneously in all the guides 75, 75 since the long links 59, 59 are pivoted at 81, 81 in juxtaposed relationship to the short links 43, 43. This vertical movement may be achieved in two ways; first, when solenoid 32 is energized, and second, when levers 85, 85 are actuated. Levers 85 are pivoted on upper shaft 41 and are located at either end thereof, where they may be conveniently reached by the operator. The device is so designed that the upper movable framework constitutes by far the greater proportion of the total weight, so that when the operator lifts grips 25 and 26 to raise the device, the claws have a tendency to close due to the weight of the movable framework. Depression of levers 85, 85 raises the movable framework through links 66, 66 which are pinned to the lever at 87, 87 at one end, and to the shaft 57 at their other end. Therefore, when the operator desires to position the carrying apparatus over a group of bottles in a case, he ordinarily holds the claws open by depressing both levers 85, 85 (Fig. 9). As soon as the carrier has been placed over the bottles with the claws opened, the operator releases levers 85, 85 and then closes switch 88 which energizes solenoid 32, thus locking the jaws around the bottle necks. With the solenoid still energized, the operator then raises the carrier to extract the set of bottles from the case 53.

In the event that there is any tendency for the

case 53 to adhere to the bottles, the operator then closes switch 88 which energizes solenoid 90 to actuate the four strippers 91, 91. Solenoid 90 is mounted on brackets 92 and 93 which are in turn secured to platform 64 by means of rivets 94, 94. The armature 95 of solenoid 90 is provided with two elongated slots 96, 96 that carry pins 97, 97 secured to the ends of actuating arms 98, 98 (Fig. 6). Arms 98 are pivoted to brackets 99, 99 at 100, 100 and in the normal unenergized position the arms extend outwardly and upwardly at about 45°. Both arms 98, 98 are resiliently retained in this "at rest" position by means of helical extension springs 101, 101 which are anchored to brackets 102, 102. The outer ends of arms 98, 98 are slotted at 103, 103 and carry rollers 104, 104 which are retained by means of U-shaped clips 105, 105 and screws 106, 106. Each roller 104 carries a tie rod 107 which is adjustably secured to the upper end of the stripper shafts 91, 91 by means of nuts 108, 108. The opposite ends of stripper shafts 91, 91 are provided with star-shaped abutments 109, 109 which are positioned and shaped to engage the usual sections or compartment walls 110, 110 in the case 53. It will thus be understood that when solenoid 90 is energized, the stripper rods 91, 91 journaled in frame members 66, 67 and 50, 50 push the case 53 and compartments 110 away from the suspended group of bottles.

When the case has been completely disengaged from the bottles, the operator (with solenoid 32 energized to lock the claws) then transports the carrier and bottles to the location where the bottles are to be deposited. In order to release the bottles, it is only necessary for the operator to open switch 88 and lift the carrier vertically upwards. Ordinarily, the weight of the bottles is sufficient to spread jaws 78 enough to clear the bottle necks. However, to insure that the jaws are open, the operator may if desired, depress handles 85, 85 to completely open the claws.

We have found that a smaller and lighter weight carrier assembly may be made if the solenoids 32 and 90 are replaced with one or more pneumatic cylinders. In this way, the overall height of the carrier may be reduced and the levers 85, 85 and switches 88, 89 may be eliminated. Fig. 10 shows such a carrier and it will be understood that the framework and claw assemblies are identical to that previously described in conjunction with Figs. 1-9. In this form, we provide a pneumatic cylinder 115 which is secured to platform 64 by means of machine screws 116, 116. The piston 117 in the cylinder 115 is secured to a piston rod 118 that is pinned to upwardly disposed ears 119, 119 of bracket 31 by pin 120. The bottom cylinder head 121 of cylinder 115 is attached thereto by means of screws 122, 122 and is provided with a suitable port 123 connected to an airline fitting 124. In a similar manner, the upper cylinder head 125 is provided with fitting 126. It will thus be understood that vertical movement of the piston 117 with respect to cylinder 115 provides the same clamping action in the claw assemblies that was described in conjunction with solenoid 32.

The stripper shafts 91a, 91a in the modified form are somewhat shorter and extend into pneumatic cylinders 130, 130, 130, 130 in which they are attached to pistons 131, 131. Cylinders 130, 130 are mounted at their bottom ends to frame members 66 and 67 and are supported at their upper ends by means of brackets 132, 132 which are riveted to platform 64 at 133, 133. The upper

ends of cylinders 130, 130 are connected to header 134 through conduits 135, 135, whereas the lower ends of cylinders 130, 130 are connected to header 136 by conduits 137, 137. A modified housing 71a encloses these cylinders and their associated structure, as shown in Fig. 10.

An important feature of the pneumatic embodiment of our carrier resides in the single, multi-port selector valve 140 whereby the entire sequence of operation is performed using only three positions of the valve control lever 141. Referring now to Figs. 12-20, selector valve 140 is provided with four radially disposed ports 142, 143, 144 and 145. Port 142 is connected to header 134 through conduit 149 and fitting 142a. Port 143 is connected to header 136 through conduit 146 and fitting 143a. Port 144 is connected to the top of cylinder 115 through conduit 147 and fitting 144a, while port 145 is connected to the bottom of cylinder 115 through conduit 148 and fitting 145a.

The stator or housing 150 in which ports 142, 143, 144 and 145 are located also journals a barrel or rotor 151 (Figs. 18 and 19). Rotor 151 has an actuating shaft 152 to which the lever 141 is connected by means of a set screw 153. The rotor is spring-loaded by means of a torsion spring 154 anchored to one of the screws 155 which secures cap 156 to the stator. Rotor 151 is provided with six radial ports 157, 158, 159, 160, 161 and 162, all of which communicate with a central chamber 163 in the rotor. In addition to the above six long radial ports, the rotor is also provided with four short radial ports 164, 165, 166 and 167 which provide axial communication with four ports 168, 169, 170 and 171 in the end wall 150a of stator 150. Ports 169-171 permit venting of the five cylinders in accordance with the position of rotor 151, through chamber 172 and vent 173. Fluid pressure for actuating all of the cylinders is supplied from some external pressure source (not shown) and a suitable regulator if desired. From thence the fluid is carried to valve 140 through a flexible hose 174 attached to fitting 175 on cover 176. Chamber 163 is in communication with flexible hose 174, as shown clearly in Fig. 14.

From the foregoing description of the operation of our bottle carrier, it will be understood that when the operator is ready to place the carrier on a set of bottles in the case, the strippers 109, 109 should be elevated and the claws 33 opened. This of course, means that pistons 131, 131 as well as piston 117 should all be raised in their respective cylinders 130, 130 and 115. Spring 154 automatically positions rotor 151 and lever 141 to connect the various ports and conduits for raising all the pistons, as shown in Figs. 12-15. In this case, conduit 149 communicates with the exhaust chamber 172 and vent 173 through ports 142, 167 and 168. Likewise, conduit 147 communicates to the exhaust chamber 172 through ports 144, 166 and 170. Pressure to the bottoms of all the cylinders is supplied through air hose 174 and chamber 163. Pressure to raise pistons 131 in stripper cylinders 130, 130 is supplied through ports 141, 143 and conduit 146. Pressure to raise piston 117 in cylinder 115 is supplied through ports 145, 145 and conduit 148. For the above setting, the rotor is turned counterclockwise against stop 177 (Fig. 15).

As soon as the operator has positioned the carrier over a set of bottles, he then depresses lever 141 to the intermediate position shown in Fig. 16. Since this is only a temporary setting

of the valve, a click detent 178 is secured to a collar 179 by screws 179a, 179a. Collar 179 is mounted on shaft 152 and secured thereto by means of set screw 180. The detent 178 turns with collar 179 and the intermediate valve position is detected when the detent registers with notch 181. Likewise the collar controls both extreme positions by means of abutments which alternately contact stop 171. In the intermediate position, the pistons 131, 131 and cylinders 132 are retained at the top of the cylinders by means of pressure through ports 162, 143, conduit 146, and venting of conduit 149 through ports 142, 164 and 168. The claws however, are actuated when pressure is introduced to the top of cylinder 115 through conduit 147, ports 144, 159, and chamber 163. Likewise, the bottom of cylinder 115 is vented through conduit 148, ports 145, 165 and 169 (Fig. 16).

With the claw assemblies tightly closed around the bottle necks, the operator lifts the bottles out of the case 53. In the event that it is necessary to strip the case from the bottles, the operator turns valve handle 141 to its fully depressed position, in which the stop 171 is against the abutment 182 (Fig. 17). In this position, the claws are held in the closed position since the top of cylinder 115 is connected to the fluid pressure source through conduit 147, ports 144, 166, and chamber 163. The bottom of cylinder 115 is vented through conduit 148, ports 145, 168, 169, and chamber 172. The stripper pistons 131, 131 however, are actuated when the tops of the cylinders 130, 130 are connected to the fluid pressure source through conduit 149, ports 142, 157, and chamber 163. Conversely, the bottoms of cylinders 130, 130 are vented through conduit 146, ports 143, 167, and 171.

As soon as the case 53 has been removed from the set of bottles, the operator may, if he wishes, release handle 141 until the rotor 151 returns to the intermediate position shown in Fig. 16. This position of course, may be detected when the detent 178 engages notch 181. The bottles are then transported to any desired location, and when deposited, the operator merely releases handle 141 to permit the spring 154 to return the rotor to the initial position of Fig. 15, thus holding the strippers in the raised position and opening the claws.

Since the carrier is intended to be used in a relatively limited range, it is entirely possible to support the carrier, if desired, on an overhead chain or cable which may be suitably counterbalanced. In this way, the operator is not required to lift the weight of the carrier over the bottles. The electrical lead for the solenoids or

the flexible conduit 174 are provided with sufficient slack to permit ample movement over the desired operating distance.

It will thus be understood that we have provided a bottle carrier which is extremely lightweight and simple to manufacture. The use of this carrier permits greatly increased efficiency in handling sets of bottles simultaneously, and in addition is less fatiguing to the operator.

While the shape and dimensions of the carrier disclosed herein are intended primarily for removing twelve beer bottles from a case, it will be understood that the number and size of the claws and guide may readily be modified so that bottles of soft drinks, which ordinarily are shipped twenty-four in a case, as well as milk bottles, may be handled.

Having thus described our invention, we claim:

A bottle carrier assembly comprising a relatively stationary framework, a pair of hand grips secured to said stationary framework, a second framework movably mounted on said stationary framework, a plurality of inverted funnel-shaped guides mounted on the bottom of said movable framework, walls defining diametrically opposite transverse slots in said guides, a plurality of claw assemblies transversely movable through said slots in each of said guides for engaging the neck of an object when said object is inserted in the guide, a fluid responsive actuator operative upon relative movement of the frameworks to open and close said claw assemblies, four vertically reciprocating shafts journaled on said movable framework and extending below the guides, a star-shaped foot on each of said shafts, a fluid selector valve mounted on one of said hand grips, and fluid connections from said valve to each of said fluid responsive actuators.
